UNITED STATES PATENT OFFICE.

CHARLES T. DAVIS, OF BROOKLYN, NEW YORK.

SURGICAL PACKAGE AND METHOD FOR INDICATING STERILIZATION THEREOF.

1,191,572.

Specification of Letters Patent. Patented July 18, 1916.

Application filed May 24, 1916. Serial No. 99,536.

To all whom it may concern:

Be it known that I, CHARLES T. DAVIS, a citizen of the United States, residing at Brooklyn, in the county of Kings and State 5 of New York, have invented new and useful Improvements in Surgical Packages and Methods for Indicating Sterilization Thereof, of which the following is a specification.

This invention relates to a surgical package and method of indicating the sterilization 10 of certain of the contents thereof, and has particular application to a package embracing a tube containing a storing or preserving fluid in which is immersed or placed 15 a surgical suture or ligature and a fusible body, the latter being employed for the purpose of indicating when the suture or ligature has been subjected to adequate heat sterilization.

20 In the present instance, by way of illustration, I have shown and described my invention as applicable to a surgical package which consists of an inclosed hermetically sealed glass tube containing a storing or 25 preserving fluid, such for instance as toluol, and in this fluid is placed a strand, suture or ligature of catgut, or other suitable material. In preparing such a package for use by the surgeon, it is the practice to subject 30 the sealed glass tube containing the fluid and the suture or ligature to the action of heat at a predetermined degree, in order that the suture or ligature may be thoroughly sterilized so that when implanted in the body 35 of the patient, it will have no deleterious action. Should such ligature or suture be not properly sterilized, it is liable, after being implanted during a surgical operation, to produce more or less suppuration, and in 40 some cases, to set up a deadly and fatal infection.

Now as a package of unsterilized sutures of this class has the same general appearance as a sterilized package of sutures, there is, 45 so far as I am aware, no method or means by which the surgeon or other person can tell whether or not the package of sutures intended to be used has been properly sterilized, because, the process of heat sterilization, as above indicated, in no manner changes the appearance of the suture ma-

terial or of the storing or preserving fluid forming the bath for the same. Thus, if through either accident, inadvertence, or for any other reason, a person in the laboratory 55 should place or mix non-sterilized tubes or packages of this kind with those which have been sterilized, the non-sterilized packages might be sent out for use, as sterilized, with the resulting danger in their use, as above 60 pointed out.

One of the objects of my invention is to obviate the liability and possibility of unsterilized packages of sutures being mistaken for properly sterilized packages, and 65 to this end I have devised the surgical package forming the subject matter of the present invention and the novel method for positively, unmistakably and accurately indicating whether the package is sterilized or 70 non-sterilized.

Another object of the invention is the provision of a package of this class having a fusible body forming a content of the tube 75 so long as the latter remains sealed or unbroken, such fusible body constituting a permanent indication of the condition of the package so far as concerns sterilization or non-sterilization.

With the above recited objects and others 80 of a similar nature in view, the invention consists in the package and the method of indicating the sterilization or non-sterilization thereof set forth in and falling within the scope of the appended claims. 85

In the accompanying drawings, Figure 1 is a view of my improved surgical package as it appears prior to sterilization. Fig. 2 is a detail view of one form of the fusible body as it appears in the package prior to 90 the sterilization of the latter. Fig. 3 is a view in elevation of the surgical package as it appears after it has been properly sterilized. Fig. 4 is a detail view illustrating conventionally the fusible body as it appears 95 melted into the form of a slug after the sterilization of the package. Fig. 5 is a detail view, in elevation, of one member of a modified form of fusible device. Fig. 6 is a similar view of the other member of such 100 modified form of device. Fig. 7 is a view in elevation showing the member illustrated

in Figs. 5 and 6, as assembled. Fig. 8 is a view of another modified form of fusible member. Fig. 9 is a perspective view of still another modified form of fusible member.

5 Referring now to the accompanying drawing in detail, and particularly to Figs. 1 to 4, inclusive, the letter A indicates a hermetically sealed glass tube of a well known form which forms a container for 10 a bath or body of fluid B, which may be of toluol or other suitable material useful for storing and preserving suture C, which is of catgut or other material from which such sutures are commonly made. If the 15 suture is of catgut, it is preferably, though not necessarily treated by impregnating or saturating with a bath of suitable antiseptic, such as potassium mercuric iodid, or the like. Prior to its insertion in the glass tube 20 A, at the time the storing or preserving fluid and the suture are placed in the tube, I also insert in such tube a small fusible body shown at D. This fusible body, which is preferably in the nature of a small cylinder, 25 as shown in Fig. 2, may be made by cutting a section or piece from a continuous wire composed of fusible material, preferably a metallic alloy. This fusible piece or body D, which is intended to fuse or melt at a 30 predetermined degree of temperature, say about 250° Fahrenheit, is preferably made up of a suitable fusible metallic alloy, composed for instance of $\frac{1}{10}$ of 1% of silver, 40% of bismuth and 59 $\frac{9}{10}$ % of lead, al- 35 though it will of course be understood that the materials of the alloy or relative proportions thereof may be altered to suit the individual requirements. After the suture, the storing fluid and the fusible body have 40 all been placed in the glass tube, as shown in Fig. 1, the latter is hermetically sealed by the fusion of the glass and is then heated at a predetermined temperature, for the purpose of thoroughly sterilizing the suture. 45 For such sterilization I prefer to employ heat at a temperature considerably in excess of the most rigid bacteriological requirements. If, for instance, I employ heat at a temperature of 275° Fahrenheit for 50 the purpose of sterilizing the suture, I may if desired, make the fusible body D of such a composition or alloy that it will melt at this degree of temperature, or if desired, it may be made of an alloy which will melt 55 at a temperature slightly below 275° Fahrenheit, say for instance, 250° F. By having the fusible alloy melt at the suture sterilizing temperature, in the example given, 275° Fahrenheit, it will be noted that when 60 the temperature within the tube reaches such point, and the alloy melts, it will indicate not only that the outside of the tubes have been subjected to the sterilizing degree of temperature specified, but that the

heat has actually been conducted to the interior of the tube, thus without a doubt rendering sterile the contained suture. 65

Where I have spoken of subjecting the package to heat at 275° F. for the purpose of sterilization, I have merely given this 70 by way of example, for any desired degree of heat proper for the occasion may be employed. For instance, heat at a temperature of more than 250° Fahrenheit is usually 75 more than ample for killing any bacterial organisms, but as stated, I prefer to employ the heat at a temperature in excess of the most rigid bacteriological requirements.

After the package has been thoroughly sterilized through subjection to the action 80 of heat, as above mentioned, an examination of the package will show that the fuse which was placed in the tube in the form of a short cylindrical section or piece of metal or piece of wire, is melted together in a 85 shapeless mass or slug, as shown in Figs. 3 and 4, this melting of course having taken place when the temperature in the glass tube was raised to the predetermined degree in 90 the example given.

In Figs. 5, 6 and 7 I have shown a modified form of fusible device which may be employed in the container in place of the fusible body D. In the modification I employ a short shank or rod E, of a fusible 95 body or alloy, and form heads e at each end thereof. These heads are adapted to engage with the slotted ends f of the resilient flat metallic stop F, which is preferably of spring steel, the shank and strip when assembled appearing as shown in Fig. 7, the strip constituting a bowed spring held under tension. Now when a container having this assembled fusible device therein is heated to the proper sterilizing temperature, the 100 melting or fusing of the shank E will permit the expansion of the bowed spring so that the latter under the action of its tension will straighten or fly out pulling the now fusing shank in half, or dividing it 105 as will be readily understood. The whole device will thus have a dismantled appearance in the tube, clearly showing that 110 sterilization of the contents has taken place.

In Fig. 8, I have shown another modified 115 form of fusible device, in this instance a small spring wire member G being employed, said member being coiled intermediate its ends as at g the terminals g' of the member being connected together by a small 120 fusible piece or block g². This device is also seated in the tube and in operation when the fusible block g² softens or melts under the influence of the sterilizing heat the two terminals of the spring will be forced apart 125 and the connection between the same broken, thus indicating the fact that the sutures in the tube have been sterilized.

In Fig. 9, I have shown still a further modification of the invention, and one which operates on the same principle as that shown in Fig. 8, but in this case a piece of flat 5 spring steel or the like is bent into loop form to constitute the member H, the ends of which are joined by the piece or block of fusible metal h.

By making the passage so as to include 10 the fusible body as herein described, and by using such fusible body as an indicator for showing the sterilization or non-sterilization of the package, I eliminate a positive source of danger incident to the use of surgical 15 packages of this kind. I further wish to direct attention to an important feature of my invention. It will be noted that the fusible plug forms a content or part of the package itself, and that it therefore constitutes a perpetual reminder or visual indicator 20 of the condition of the specific package, in that it is ever present as a part of such package itself until the glass is broken when the suture is to be used. Thus, no 25 matter through how many hands the package may pass, such as from the laboratory of the manufacturer to the surgical supply dealer and finally to the surgeon, the fused body confined within the sealed tube will 30 always remain as a positive and visible indication that the contained suture has been properly sterilized. On the other hand, in 35 instances where the package is sterilized in the laboratory and the fact indicated by a pyrometer or other heat measuring device placed, during sterilization, within the sterilizing apparatus along with the tubes of sutures, but not inside of the latter, the only person who is aware that a particular package 40 has been sterilized is the operator who examined the pyrometer directly after the sterilization was completed, and as such pyrometer or other heat measuring device forms no part of the package itself, there is 45 no way by which it can be positively determined whether or not the package has been sterilized, once such package has been sent from the laboratory and into the ordinary 50 channels of trade. With my invention, however, the condition of the package with respect to its sterilization may be determined at a glance.

While I have herein shown and described the preferred embodiment of my invention, 55 I wish it to be understood that I do not limit myself to all the details herein set forth, as modification and variation may be made without departing from the spirit of the invention or exceeding the scope of the appended claims.

What I claim is:

1. A package comprising a sealed container having an article to be sterilized inclosed therein and a fusible substance car-

ried by the container and adapted to fuse at 65 a selected temperature and to indicate in its fused condition that the article within the container has been subjected to heat sterilization.

2. A surgical package comprising a sealed 70 container having a fusible alloy and an article to be sterilized, both inclosed within the container.

3. A surgical package comprising a sealed 75 container having therein an article to be sterilized, a storing fluid and a fusible body all inclosed therein, said fusible body melting at a predetermined temperature to indicate that the article has been subjected to a predetermined degree of heat for sterilizing 80 purposes.

4. A surgical package comprising a sealed 85 glass tube having a suture, a storing fluid and a fusible body all sealed therein, said fusible body melting at a temperature below the predetermined heat sterilizing temperature for the suture.

5. A surgical package comprising a sealed 90 glass tube having a storing fluid and an article to be sterilized inclosed therein, and a body of fusible alloy also inclosed and sealed within the glass tube, said fusible alloy being adapted to melt at a temperature below the predetermined heat sterilizing temperature for the article.

6. A surgical package comprising a sealed 95 glass tube having a storing fluid and an article to be sterilized inclosed therein, and a body of fusible metal also inclosed and sealed within the glass tube, said fusible metal being adapted to melt at a predetermined 100 temperature.

7. A surgical package comprising a sealed 105 glass tube having inclosed therein a storing fluid and a suture to be sterilized, and a fusible metallic alloy also inclosed in said glass tube and adapted to melt when the tube and its contents are subjected to the action of heat at 250° Fahrenheit and upward.

8. A surgical package comprising a sealed 110 container having therein a substance to be sterilized and an indicating device comprising a spring member and a body of fusible material holding the spring member under tension.

9. The herein described method of indicating when articles inclosed in containers have been sterilized, which method consists in providing the article-inclosing container 115 with a fusible substance, and then during the heat sterilization of the article subjecting said fusible substance to the action of the article sterilizing heat which is of a sufficient temperature to fuse or melt said 120 fusible substance.

10. The herein described method of indicating when articles inclosed in containers

have been sterilized, which method consists in an article inclosed in the container and with the article a body of fusible material, and then during the heat sterilization of the article, subjecting said fusible substance to the action of the sterilizing heat to melt the fusible substances within the container.

In testimony whereof I have hereunto set my hand in the presence of two subscribing witnesses.

CHARLES T. DAVIS.
